NEEDLE JACK PUSHER

Ladislaus Robaczynski, Brooklyn, N. Y.

Application August 28, 1936, Serial No. 98,265

1 Claim. (Cl. 66—63)

This invention relates to new and useful improvements in knitting machines and more particularly it pertains to knitting machines generally known in the art as "links and links" type.

5 "Links and links" knitting machines employ two flat needle beds mounted in the same plane. Each needle bed is provided with channels or grooves in which needles, needle jacks and needle jack pushers or sinkers travel to perform the various knitting operations. Such machines also employ a jacquard mechanism generally including a series of pattern cards provided with openings. To produce various knitting patterns, certain of these openings are plugged in such a manner that as the jacquard mechanism is operated, the plugs will engage certain of the needle jack pushers and move them, together with the needle jacks and needles into knitting position or into operative position relatively to the carriage of the 10 machines in order that these needles may be caused to perform a knitting operation. Such openings in the jacquard cards as have not been plugged receive the ends of their corresponding jack pushers and do not effect an operation 15 thereof.

The beds of machines of the type above mentioned vary. That is to say that the beds may be of different gauge, for example, a nine gauge bed is a bed in which there are nine needles to the 20 inch; a seven gauge bed is a bed in which there are but seven needles to the inch. In machines of this type generally, the beds are interchangeable and it often is the case that beds of two or more different gauges will be supplied with each 25 machine.

It is the established practice in the art to construct the beds with the needle channels deeper in the beds of lower gauge than is the case in beds of higher gauge. For example, in needle beds 30 of the so-called seven gauge type, the needle channels are deeper than is the case in needle beds of the nine gauge type.

This practice has a decided disadvantage in that, when one set of beds of one gauge is removed from a machine and substituted with another set, it requires an adjustment of the jacquard mechanism. This will be readily understood by reason of the fact that in a nine gauge bed, because of the fact that needle channels are 35 shallower, the openings in the jacquard pattern cards will register with and receive the ends of the needle jack pushers. However, when a lower gauge bed is placed upon such a machine, the needle jack channels being deeper than in the 40 nine gauge bed, the rear ends of the needle jack

pushers and the openings in the jacquard pattern cards do not register and in order to effect the desired operation, the entire jacquard bar around which the pattern cards pass, must be lowered to prevent interference of the lower edge of the 5 opening in the pattern cards with the lower edge of the needle jack pushers. Obviously, each time the needle beds placed upon the machine are of a different gauge than those for which the new needle beds are substituted, an adjustment of the 10 jacquard mechanism is necessary.

This adjustment of the jacquard mechanism is generally accomplished in machines as they are commonly constructed, by a substitution of bearings and bearing lugs for mounting the jacquard 15 bar, which operation is of a more or less tedious and time consuming nature.

It is an object of the present invention to provide a new and improved construction by means of which any adjustment of the jacquard mechanism is unnecessary when substituting needle beds 20 of one gauge for beds of a different gauge.

It is a further object of the invention to accomplish the object afore-mentioned by employing a needle jack pusher of new and novel construction. 25

Still a further object of the invention resides in the provision of a new and novel form of needle jack pusher which may be more readily placed in and removed from operative position in the needle bed, than is possible with needle jack pushers as 30 generally constructed.

With the above and other objects in view, reference will be had to the accompanying drawing, in which:

Figure 1 is a fragmentary transverse sectional 35 view taken in a vertical plane of the rear portion of a knitting machine bed and jacquard mechanism,

Figure 2 is a similar view with the jacquard mechanism removed, illustrating the manner in 40 which the new and improved jack pusher may be more easily removed from the needle bed channels,

Figure 3 is a perspective view of the improved needle jack pusher, and;

Figure 4 is a view similar to Figure 1 illustrating the manner of operation of the new and improved needle jack pusher as compared to a needle jack pusher of conventional type.

Referring to the drawing by reference character, 10 designates a portion of the knitting machine frame, 12 one of the needle beds and 14 one of the channels in the needle beds in which the jacks 16 and jack pushers 18 ride. Mounted to the rear of the needle bed 12 there 50 55

is a jacquard bar 20 which is rotated or oscillated as the case may be. Passing around this jacquard bar 20 there is a series of jacquard cards 22 hingedly connected together as at 23. These 5 cards carry openings 24 and certain of the openings are adapted to be closed by plugs 26.

So far as described the construction is of conventional form and operates in the following manner. With the parts in the position in which 10 they are shown in Figure 1 in full lines, when the jacquard bar is moved forwardly to its dotted line position in said figure, the rear end of the jack pushers will enter the openings 24 in the jacquard pattern cards which do not carry plugs, 15 while those openings which are plugged, will be closed by the plug in such manner that the plugs will engage the rear ends of their respective needle jack pushers 18 and move the same forwardly into engagement with the needle jacks 20 16 and force them forward to position to be picked up by the cams of the carriage, which latter are not shown.

A needle jack pusher constructed in accordance with the present invention is illustrated in 25 Figure 3 and comprises a main body portion 30 having a jack engaging nose 32 and a butt 34 for engagement in the camways of the carriage in the ordinary manner. These needle jack pushers are mounted in the channel 14 of the needle bed upon one edge, which edge is designated 30 36 and when the jack pushers are in operative position in the carriage this edge is the lower or bottom edge and rides upon the bottom wall of its respective channel 14 with the butt 34 standing upwardly above the top surface of the needle bed as illustrated in Figure 1.

In Figure 1 I have illustrated the invention applied to a needle bed, the gauge of which is nine. In Figure 4, I have illustrated by dotted lines the increased depth of the needle bed channels when the gauge is decreased or approximately what it would be in a needle bed of the seven gauge type. In said Figure 4, the dotted line 38 designates the bottom of the channel in a seven gauge bed and it will be noted that this line 38 is in a plane appreciably lower than the plane of the bottom wall of the nine gauge needle bed illustrated in Figure 1. It will be obvious that if a seven gauge bed be employed in the 45 machine, as the jacquard bar comes forward the lower edge of the openings in the jacquard cards carried thereby, would engage the rear ends of the needle pack pushers and would, therefore, operate all of said needle pack pushers. As heretofore stated, it is, therefore, necessary to adjust the jacquard bar when a bed of lower gauge is used.

To obviate the necessity of making adjust-

ments of the jacquard bar from its higher position to one of its lower positions when a bed of lower gauge is substituted for a bed of higher gauge or to raise the jacquard bar when a needle bed of higher gauge is substituted for a needle bed of lower gauge, I reduce the width of the rear end of the needle jack pusher as indicated at 40 in Figure 3. I prefer to reduce the width of the needle jack pusher by cutting out a portion of the under edge 36 thereof, as at 42, and continuing the portion 44 at an angle so that the end 40 will be of a width approximately or a little less than one-half of the width of the main body portion 30 of the needle jack pusher. 5

By reference to Figure 4 it will be noted that 15 the dotted line 38 which would be the limit of depth of channels in needle beds of relatively low gauge, clearly passes the lower edge of the opening 24 in the jacquard card which is in operative position in said figure, it being understood that 20 in this figure, the jacquard bar 20 has not been adjusted.

As heretofore stated the needle jack pushers ride in the channels upon their lower edge and this cut out portion 42 is formed upon the lower edge so that regardless of the gauge of needle bed employed, the jack pushers will at all times properly register with and pass into such openings of the jacquard pattern cards as are not closed by plugs 26 and this without adjustment 30 of the jacquard bar 20.

Another advantage of such a construction resides in the fact that it provides a rocking or tilting point 50 upon the lower edge of the needle jack pusher and about which the needle jack 35 may be rocked by engagement of a tool 52 with its rear end, thus elevating the forward end of the jack pusher to a position where it may be easily or readily gripped by the hand and thereby removed from the needle bed. 40

From the foregoing it will be apparent that the present invention provides a new and improved construction of needle jack pusher which is capable of use in needle beds of all gauges without requiring the adjustment of the jacquard 45 bar as is the case in all present machines of this type with which I am familiar.

Having thus described the invention, what is claimed as new, is:

A needle jack pusher comprising a relatively 50 thin elongated body portion adapted in operation to ride upon one of its edges, said member having a portion of its riding edge cut away to provide a relatively long reduced tapering rear end extension and a fulcrum about which the jack pusher may be rocked to elevate the forward end thereof.

LADISLAUS ROBACZYNSKI.
